WEIGHING SCALE

Burns S. Watling, Chicago, Ill., assignor to Watling Scale Company, Chicago, Ill., a corporation of Illinois

Application December 15, 1939, Serial No. 309,354

13 Claims. (Cl. 194—92)

This invention relates to weighing scales, and more particularly to a known type of coin-controlled scale wherein the customer or user is given an opportunity to estimate or guess his own weight, and if he guesses his weight correctly the coin is returned to him by the machine.

Scales of this type commonly employ a pair of scale discs, one of which is weight-actuated while the other is manually set by the customer to his estimated weight before the weight-actuated disc is released. If the weight-indicating numbers or marks on the two discs tally or register with each other, the coin is returned. If they do not, the coin is sent to the coin box of the machine.

A scale of this type forms the subject-matter of an application for Letters Patent heretofore filed by me on the 3rd day of April, 1939, Serial No. 265,800. In my aforesaid application the two discs are mounted side by side on a common shaft, and the adjacent sides of the manually set disc and the weight-actuated disc are provided, the former with lateral pins and the latter with a corresponding row of holes. By means of a tensioned spring normally locked against action, the manually set disc is shifted toward the weight-actuated disc. If the estimated weight agrees with the actual weight within a few ounces as shown by the scales on the discs, the pins will pass through the holes, and this will set in action a coin disposal mechanism by which the deposited coin is returned. If the guess is incorrect, a lesser movement of the shiftable disc occurs, and the coin is in that case diverted to the coin box of the machine.

The spring which actuates the disc shifting mechanism is, when a proper coin is deposited, released for action by a manually operated mechanism energized by a horizontal slideable plunger which receives the deposited coin, the latter constituting an element of said manually operated mechanism; and, if no coin is deposited, the disc shifting mechanism will not operate.

The coin disposal mechanism is operated to either return the coin to the customer or send it to the coin box by an arm that, in turn, is swung by a rock shaft constituting an element of the disc-shifting mechanism.

Fast on the shaft which mounts the two discs is a ratchet wheel, and cooperating therewith is a detent pawl which is normally held engaged with the ratchet by a spring, and this pawl is disengaged from the ratchet wheel to permit the weight-actuated scale to turn by a detent release

mechanism that includes a rock shaft operatively connected to said detent, and a spring-impelled member that is first shifted into a position to actuate said rock shaft by the manually impelled plunger and is then caused to actuate said rock shaft by its spring.

The scale of the present invention, which is an improvement on that of my application Serial No. 265,800, is equipped with a vertically disposed coin-controlled detent release mechanism that is operated manually by a crank shaft and handle, and that is more fool-proof and less subject to abuse and failure to function properly than the plunger-operated detent release mechanism of my aforesaid application. This vertically disposed coin-controlled detent release mechanism forms the subject-matter of an application for Letters Patent, Serial No. 309,355, filed by me on the 15th day of December, 1939; and one object of this invention has been to provide a disc shifting mechanism adapted for properly timed cooperation with and actuation by the vertical detent release mechanism of my last mentioned application. Another object has been to provide an improved coin disposal mechanism likewise adapted for cooperation with, and actuation by, said detent release mechanism, and selectively controlled by a movable member of the disc shifting mechanism.

Other objects and inherent advantages of the invention will appear later in the following detailed description of an improved embodiment of the invention illustrated in the patent drawings, in which—

Fig. 1 is a front elevation of the scale, with the front cover plate removed and the front wall of the cap broken out, and showing the detent release mechanism, the disc shifting mechanism, and the coin disposal mechanism in normal idle positions.

Fig. 2 is a perspective view of the immediate detent pawl lifting and lowering mechanism located in the cap or cover of the scale housing, that is operated by the underlying coin-controlled mechanism.

Fig. 3 is an enlarged front elevation of the coin-controlled detent release mechanism, including a portion of the coin chute with its front cover plate removed, and also showing in dotted lines an actuating portion of the disc shifting and coin disposal mechanisms that is itself actuated by a movable element of the detent release mechanism.

Fig. 4 is a vertical section on the line 4—4 of Fig. 3.

Figs. 5, 6 and 7 are views similar to Fig. 4, showing different positions assumed by the parts during the operation of the detent release mechanism.

Figs. 8, 9 and 10 are front elevation views of the scale discs, disc shifting mechanism, coin disposal mechanism, and handle-operated push bar of the detent release mechanism, showing different positions assumed by the parts.

Fig. 11 is an enlarged fragmentary vertical section taken on the line 11—11 of Fig. 10, showing a position of the coin switch in which the coin goes to the coin box of the scale.

Fig. 12 is an enlarged fragmentary vertical section taken on the line 12—12 of Fig. 9, showing a position of the coin switch in which the coin is deflected into the coin return chute.

Fig. 13 is a rear elevation of the lower half of Fig. 3, showing in full and dotted lines extreme positions of the actuating portion of the disc shifting and coin disposal mechanism that appears in dotted lines in Fig. 3.

Fig. 14 is an enlarged side elevation of parts of the disc shifting and coin disposal mechanisms appearing in the lower left-hand corner of Fig. 8, and also showing a gear train and wind vane for slowing the action of a pivoted sector lever that appears in one extreme of its movement.

Fig. 15 is a view similar to Fig. 14, but showing the sector lever at the opposite extreme of its movement.

Fig. 16 is a sectional view taken on the line 16—16 of Fig. 14.

Fig. 17 is an isolated front plan of one of the vertically movable plates of the detent release mechanism.

Fig. 18 is a longitudinal section, on the line 18—18 of Fig. 3, through the foundation plate, one of the vertically slidable plates on the foundation plate, and the sectional push bar that moves said vertically slidable plate downwardly.

Fig. 19 is a perspective elevation of the other vertically movable plate of the detent release mechanism.

Fig. 20 is a perspective view of a coin-arresting pan.

Referring to the drawings, and more particularly Figs. 1, 2, 8, 9 and 10, the scale in which my present improvements are embodied employs a pair of scale discs 20 and 21 mounted side by side on a shaft 22 the disc 20 being fast on the shaft and weight-actuated, and the disc 21 being loose on the shaft and manually set by the customer to his estimated weight, before the weight-actuated disc 20 is released, by turning a knob 23. Disc 21 is also shiftable toward and from the weight-actuated disc 20 by mechanism later described. The disc 21 is equipped with pins 24 that project toward the disc 20, and the latter is formed with a corresponding number of similarly spaced holes 25 (Fig. 9). If the user has correctly guessed his weight within a few ounces either way, the holes 25 will register with the pins 24, and when disc 21 is shifted sidewise, by mechanism later described, the pins will pass through the holes (Fig. 9); and, through mechanism later described, the coin is returned to the user. If the guess is incorrect, the holes do not register with the pins, and the latter can be moved only into contact with the solid portions of the disc 20 (Fig. 10), and in that event the coin is sent to the cash box of the machine.

The parts as thus far described and shown are substantially identical with corresponding

parts disclosed and claimed in my aforesaid application Serial No. 265,800.

Again referring to Figs. 1 and 2, 26 designates the base, 27 the upright portion of the scale casing, 28 a cover or cap mounted on the upright portion 27 and housing the scale discs, and 29 the scale platform. As usual in scales of this type, the platform 29 is connected through a rod 30, a frame 31 containing a dash pot 32 to steady the movement, a pivoted cross-bar 33 on the upper end of frame 31, and flexible straps 34 to pivoted sector cams (not shown) from which are suspended swinging counterbalance weights 35; and from a yoke 36 in which the cross-bar 33 is pivoted a rod 37 extends upwardly and is connected to the lower end of a rack bar 38 that engages with a pinion 39 fast on the disc shaft 22. A detent pawl 40, pivoted at 41, is normally engaged with a ratchet disc 42 fast on the shaft 22 so as to prevent the turning of the scale disc 20 until the detent pawl 40 has been raised.

All of the above last described parts are old and well known, and need not here be more particularly described.

In Fig. 2 I illustrate a simple mechanism for directly lifting the pawl 40 to free the shaft 22 which is adapted to cooperate with the coin-controlled detent release mechanism forming the subject-matter of my aforesaid application Serial No. 309,355, and which is also shown and described in said application. This immediate pawl lifting mechanism comprises a rock shaft 43, oppositely extending arms 44 and 45 fast on shaft 43, a link 46 pivotally connecting arm 44 to pawl 40, an upstanding arm 47 also fast on shaft 43, and a pull spring 48 acting on arm 47 in a direction to normally apply the pawl 40 to the disc 42. Pivoted to and depending from the arm 45 is a link 49, to the lower end of which 40 is adjustably attached a foot 50 formed with a vertical slot 51 continuous with the lower end of an inclined cam slot 51', and a laterally offset toe 52. A down pull on toe 52 releases the detent pawl 40.

Since the vertically disposed coin-controlled detent release mechanism forming the subject-matter of my aforesaid application Serial No. 309,355 cooperates with and actuates both the disc-shifting mechanism and the coin disposal mechanism of this application, I have herein illustrated the same with sufficient fullness to enable its structure and operation to be clearly understood.

Describing this coin-controlled detent release mechanism, in the cap 28 is the receiving mouth 53 of a downwardly extending coin chute partially indicated at 54 in Fig. 1 that communicates at its lower end with an inclined section 55, this latter communicating at its lower end with the upper end of a vertical section 56 (Fig. 3), this latter having a sloping bottom wall 57 over which the coin rolls into a lower vertical section 58 and thence to the coin disposal mechanism.

Formed as an edgewise extension of the rear wall of the chute parts 56, 57 and 58 is a vertical foundation plate designated as an entirety by 59, on which two vertically movable members 76 and 89 are slidably mounted and guided, member 76 being spring impelled in an up direction and positively moved down by the down swing of a manually operated handle 60 (Figs. 1, 8, 9 and 10), and member 89 being spring impelled in a down direction and raised by said first named member into temporary engagement with the toe 52 of the foot 50.

On one lower corner of the foundation plate 59 are a pair of lateral lugs 61 supporting a pivot pin 62, on which is mounted the lower end of a control member of the detent release mechanism designated as an entirety by 63. This control member 63 is a flat, upright bar disposed in a plane at right angles to the plane of the coin chute, and it is urged to swing inwardly toward the coin chute by a torsion spring 64 (Fig. 13) encircling the pivot pin 62, and anchored at one end to one of the lugs 61 and at its other end bearing on the transverse limb of the loop-shaped lower end of the member 63. On the upper end of the member 63 is a vertical stop shoulder 65, and at the base of the latter is a horizontal finger 66, these parts being movable across the lower portion of the chute section 56, and, when a coin C is deposited, engaging the latter in a manner shown in Fig. 7, temporarily arresting the coin, the latter at the same time blocking further inward swing of the member 63. Next below the finger 66 is a transverse slot 67 that straddles the inclined bottom wall 57 and permits the maximum inward swing of member 63 shown in Fig. 5, which occurs when an attempt is made to operate the scale without depositing a coin. In the body of the member 63, below the transverse slot 67, is an irregularly shaped longitudinal slot, the edges of which are so formed as to provide a stop shoulder to block actuation of the detent release mechanism when no coin is deposited, and also inclined surfaces or cams that, in cooperation with a finger on one of the vertically slideable members, effect the outward swing and control the inward swing of the member 63. On the left edge of the slot, viewing Figs. 4, 5, 6 and 7, is a cam 68, a stop shoulder 69, and an oppositely inclined cam 70. On the right edge of the slot is a steep cam 71, and a cam 72 opposite the cam 70. The portion of the slot between the cam 71 and the stop shoulder 69 forms a throat 73 for the normal down passage of the finger of the slideable member, and narrow upper and lower end portions 74 and 75 of the slot cooperate with said finger to hold the member 63 in the position shown in Figs. 4 and 6 respectively. The functions of these several cams of the slot will appear in the description of the operation.

Describing next the two vertically slideable members that are mounted on the foundation plate 59, 76 designates as a whole a flat plate that is formed with vertically aligned upper and lower slots 77 and 78, continuous with the lower ends of which are inclined cam slots 77' and 78'. Upper and lower headed studs 79 and 80 mounted in the plate 59 extend through these slots and both confine the plate 76 on the plate 59 and guide the plate 76 in its vertical and lateral movements. Plate 76 is located next to the coin chute parts 56, 57 and 58, and on the edge thereof adjacent to said parts is an integral horizontal finger 81 that extends behind a vertical guide bar 82 secured to the plate 59 and through the longitudinal slot of the control member 63. On the upper end of the other edge of plate 76 is a horizontal trip lug 83, and on the lower end of the same edge is a toothed rack 84 cooperating with a spring held dog 85 to form a well-known full stroke compelling device. A pull spring 86 anchored at its lower end to a pin 87 on the plate 76 and at its upper end to a pin 88 (Fig. 1) on the coin chute section 55 urges the plate 76 upwardly.

The other vertically slideable member consists of a plate designated as an entirety by 89. This

plate 89 is also formed with vertically aligned upper and lower slots 90 and 91, through which extend headed guide studs 92 and 93 mounted in the plate 59. Plate 89 is mounted alongside plate 76, and is normally urged downwardly by a pull spring 94 anchored at its upper end to a lug 95 on the outer edge of plate 89 and at its lower end to a pin 96 on plate 59. Pivoted on the front face of plate 89 about midheight of the latter at 97 is a trip lever 98 that is formed on its lower edge with a forwardly projecting lug 99 that lies in the path of the trip lug 83 during the rising movement of the latter. A pull spring 100 normally holds lever 98 in the horizontal position shown in Figs. 3 and 19. Lever 98 can swing downwardly, but not upwardly beyond the horizontal position shown, due to a tail piece 101 thereon engaged with one vertical edge of the plate 89. A sufficient down swing of lever 98 and its lug 99 can occur, because the tail piece 101 is below the level of its pivot axis 97. Also pivoted at 102 on the upper end of plate 89 is another trip lever 103 and normally held in the horizontal position shown by a pull spring 104 and a stop lug 105. The nose 106 of this lever can swing downwardly, but not upwardly beyond the horizontal position shown. As the plate 89 rises, the nose 106 wipes across the toe 52 of the foot 50, and, as the plate 89 later descends under the pull of its spring 94, the nose 106 engages the toe 52 and draws the foot 50 and link 49 downwardly, thus raising the detent 40 from the ratchet wheel 42, and permitting the scale disc 20 to turn.

The normal position of plate 76 is its fully raised position shown in Fig. 3; the normal position of plate 89 is its fully lowered position shown in Fig. 3; and the normal position of foot 50 is its fully raised position shown in Figs. 1, 2 and 3. The trip lug 83 and trip lever 98 constitute what I term a lift-and-let-go connection between the plates 76 and 89; and the lever 103 and toe 52 constitute what I term a pull-and-let-go connection between plate 89 and foot 50. The separation of the lugs 83 and 99 is effected during the latter portion of the rising movement of plate 76 by the engagement of the cam slots 77' and 78' with the guide studs 79 and 80, which effects a lateral shift of plate 76 away from the plate 83. The separation of the toe 52 from lever 103 is effected during the latter part of the down movement of foot 50 by a lateral shift of the latter away from the plate 89 due to the engagement of the cam slot 51' with a fixed guide stud 107 engaged with the slots 50', 51'.

Describing next the manually operated means for forcing the plate 76 and its finger 81 downwardly, fast on the hub of the handle 60 is a crank arm 108 (Figs. 1, 8, 9 and 10), and pivoted to the outer end of arm 108 is a depending link 109 that is adjustably secured at its lower end by a screw and slot connection indicated generally by 110 (Fig. 3) to the upper end of a push bar 111 that is operatively connected to the plate 76. To provide for a cushioned down thrust of the push bar and the transmission of a corresponding down push on the plate 76, the push bar is preferably made in a pair of spring-connected sections, as follows. Referring to Figs. 3 and 18, 111 designates the front section of the push bar, in which is a long, continuous, longitudinal slot 112 that slidably engages a guide stud 113 mounted in the plate 76, so that the push bar section 111 may have a combined downward and swinging movement as the handle

60 is operated. Lying behind and in sliding contact with the rear side of the push bar section 111 is a shorter push bar section 114, the lower end of which is stepped on the stud 113. The section 114 is formed with a longitudinal slot 114' in part registering with the upper portion of the long slot 112 in section 111. A headed stud 115 mounted on section 111 slidably engages the slot in section 114, and a headed stud 116 mounted on section 114 slidably engages slot 112. Through a strong pull spring 117 anchored at its lower end to a hook 118 on one edge of bar 111 and at its upper end to a lug 119 on the upper end of bar 114 a down thrust on bar 111 is transmitted in cushioned form to bar 114, and, through the latter and stud 113, to plate 76. The return or upward movement of the push bar is effected by a pull spring 120.

Describing the operation, when the scale is idle the parts are in the position shown in Figs. 1-4 inclusive, the finger 81 being in the upper end 74 of the longitudinal slot of the control member 63 and locking the latter in the position shown in Fig. 4. A customer steps on the platform 29 and, having set the scale disc 21 to his estimated weight, deposits a proper coin in the chute, the coin coming to rest on the finger 66. The handle 60 is then swung downwardly clockwise viewing Fig. 1, which, through crank arm 108, linking 109, and cushioned push bar 111, 117, 114, forces plate 76 downwardly. During the first part of the down stroke the plate 76 is lowered sufficiently to carry finger 81 out of the upper end 74 of the slot, and this permits the control member 63 to swing inwardly until the shoulder 65 strikes the coin, as shown in Fig. 7, arresting the inward swing of member 63 at a point where the throat 73 of the slot is in the path of the descending finger 81. Further down swing of handle 60 carries finger 81 down through throat 73, and, as finger 81 encounters and slides down cam 70, member 63 is cammed outwardly, as shown in Fig. 6, releasing the coin and permitting it to roll down inclined wall 57 and thence to the coin disposal mechanism. At the end of the down swing of handle 60 the finger 81 is in the lower end 75 of the slot, and member 63 is temporarily locked in the position shown in Fig. 6. During the down movement of plate 76 the latter is shifted laterally to the right, and its lift lug 83 wipes idly over lug 99 of lever 98, slightly rocking the latter, and assumes a position beneath lug 99. Under the pull of spring 120 the push bar is raised, restoring handle 60 to normal position, and leaving plate 76 free to rise under the pull of its spring 86. As plate 76 rises, it raises plate 89, through engagement of lift lug 83 with lever lug 99, to its highest position, the nose 106 of lever 103 wiping idly past toe 52 during the rising movement. During the final part of this rising movement, when lever 103 has been carried above toe 52, plate 76 is shifted laterally back, thus disengaging lug 83 from lug 99, and allowing spring 94 to suddenly pull plate 89 down. This causes the nose 106 of lever 103 to strike toe 52 and draw down the foot 50 and link 49, thus releasing the detent of the scale weighing disc. During the final part of the down movement of foot 50, its cam slot 51' shifts the foot to the left, thus disengaging toe 52 from lever 103, and allowing plate 89 to descend to its fully lowered position. During the rising movement of the plate 76 its finger 81, of course, travels upwardly from its Fig. 6 position through its Fig. 7 position, its sliding engagement with cam

72 shifting throat 73 into its path of travel, and its later sliding engagement with cam 68 rocking member 63 outwardly to permit the finger to enter the upper end 74 of the slot, as shown in Fig. 4.

The foregoing describes a complete cycle of the detent release mechanism when a proper coin has been deposited.

If now it be attempted to operate the scale without depositing a coin, there will be no coin to arrest the inward swing of control member 63 at the position shown in Fig. 7, in which position the throat 73 is in the path of the finger 81, and the result is that the spring 64 swings member 63 to the limit of its inward movement shown in Fig. 5, wherein the stop 69 lies across the path of the descending finger 81 and arrests further descent of the latter. And if it be attempted to beat this, by giving the handle 60 a quick, slamming movement, the sharp impact of finger 81 on the cam 71 accelerates the swing of control member 63 and throws the throat 73 across and beyond the path of the finger before the latter can enter the throat, so that the finger will, in that case also, be arrested by the stop 69, as shown in Fig. 5. Hence, whether the handle be given a slow, even down movement or a quick, slamming movement, the detent release mechanism will not be actuated without the previous deposit of a coin.

Describing next the mechanism for shifting the manually set scale disc 21 toward and from the weight-actuated disc 20, and referring to Figs. 1, 8, 9, 10, and 13 to 16, the prime mover for shifting disc 21 toward disc 20 is a spring that is normally locked against functioning until a coin has been deposited, and the prime mover for later shifting disc 21 away from disc 20 is another spring acting through a cam. Suitably journaled beneath and crosswise of the shaft 22 is a rock-shaft 121, and fast on this rock-shaft are a pair of upstanding arms 121' carrying pins 122 that engage with a grooved collar 123 that is fast with the hub of disc 21. Fast on rock-shaft 121 is a depending arm 124. Pivoted on a stud 125, that lies opposite the outer side of ratchet disc 42 and is parallel with rock-shaft 121, is an elbow lever having a depending arm 126, and a shorter outwardly extending arm 127. A link 128 pivotally connects the lower ends of arms 126 and 124. Integral with and extending outwardly from the lower end of arm 124 at an angle to the latter is an arm 129. An endwise movable vertical bar 130 has a pin and slot mounting 130' on a fixed bracket plate 131 (Figs. 1 and 16), and in its upper end is a vertical series of holes 132 by which the bar may be pivoted to the short arm 127 of the elbow lever. The bar 130 is urged downwardly by a pull spring 133 best shown in Fig. 16, that is anchored at its upper end to a hook 134 on bar 130 and at its lower end to a fixed stud 135 on bracket plate 131 extending through a slot 136 in bar 130. On the lower end of bar 130 is a pin 137 carrying a roller 138.

Describing next a governor-controlled means that controls the inward shift of disc 21 and effects its outward shift and is itself actuated in one direction by a bar in turn actuated by the vertically movable member 76 of the detent release mechanism, and in the reverse direction by a spring, 139 designates a sector shaped lever that, as best shown in Figs. 14 and 16, is fast on a squared hub 140 keyed to the initial shaft 141 of a speed multiplying gear train designated as a whole by 142, the final shaft 143 of the train

mounting a wind varie 144. The initial gear 145 is loose on shaft 141, and is driven in a contra-clockwise direction only by a ratchet 146 fast on shaft 141 and a pawl 147 pivoted on gear 145. The gear train as a whole is mounted and supported on a fixed bracket plate 148 beneath the bracket plate 131. This device is in the nature of a pneumatic governor or timer for slowing and steadyng the swinging movement of the sector lever 139 in a contra-clockwise direction. A pull spring 149 (Fig. 1) constantly urges the sector lever in a contra-clockwise direction.

Loosely pivoted on the hub 140 and lying directly behind the sector lever 139 (Fig. 16) is a stop arm 150 formed with a squared upper edge 151 that, in the idle position of the parts shown in Figs. 1, 8, 14 and 16 underlies the roller 138 and blocks the down movement of bar 130 and the inward shift of disc 21; and just inwardly of the squared edge 151 is a cam 152 which, during the final part of the contra-clockwise swing of sector lever 139, engages the roller 138, lifting bar 130, and returning disc 21 to its normal idle position shown in Figs. 1 and 8. Stop bar 150 carries a lateral pin 153 that extends through an arcuate slot 154 in the sector lever for displacing and returning the stop arm 150 from and to its stop position. The broad edge of the sector lever is formed with an arc 155 struck from the pivot axis of the lever, a stop 156 at the outer end of the arc for the roller 138 (Fig. 15), and incline 157 at the inner end of the arc facing the cam 152 and forming with the latter a wide V-shaped notch into which the roller 138 may drop when the two discs 20 and 21 are in the coin return position shown in Fig. 9. A fixed stop 158 limits the swinging movement of both the sector lever and the stop arm to the left.

When a proper coin or token has been deposited, the sector lever and stop arm are swung clockwise from the position shown in Fig. 14 to that shown in Fig. 15, tensioning the spring 149, by a lost motion connection to the plate 76 of the detent release mechanism. This connection includes an elbow lever that is pivoted at 159 (Fig. 13) on the rear side of the foundation plate 59. The substantially horizontal arm 160 of this elbow lever has a widened free end in which is an opening 161 that overlaps a vertical slot 162 in the plate 59, and through this slot and the opening 161 passes a rearward extension 113' of the stud 113. The opening 161 is sufficiently larger than the diameter of the stud extension 113' to allow a limited down movement of the latter before it begins to actuate the elbow lever. To the upper end of the upstanding arm 163 of the elbow lever is pivoted at 164 one end of a transversely extending push bar 165, the other end of which push bar has a longitudinal slot 166 engaged with a lateral pin 167 in the lower narrow end of the sector lever 139.

Describing the operation of this disc-shifting mechanism, if no coin has been deposited, the stud extension 113' moves idly through the elbow lever opening 161 to the dotted position shown in Fig. 13, but does not swing the lever, and consequently no disc-shifting movement occurs. But if a coin has been deposited, stud extension 113' makes a full down movement, rocking the elbow lever to the dotted position shown in Fig. 13, and, through the push bar 165, swinging the sector lever 139 from the position shown in Figs. 1, 8 and 14 to the position shown in Fig. 15. During this movement the left end of slot 154 strikes the pin 153, transferring the load of roller 138

from the stop arm 150 to the arc 155 of the sector lever, as shown in dotted lines in Fig. 14, and swinging stop arm 150 out of its vertical position and the stop arm then drops by gravity until its pin 153 strikes the right end of slot 154; further swing of the sector lever and stop arm being prevented by the engagement of stop 156 with roller 138 (Fig. 15). This tensions the spring 149 of the pneumatic governor, and opens up the notch formed by the cam 152 and the incline 157. The pin and slot connection of the push bar 165 to the sector lever enables the push bar to shift back to starting position as operating handle 60 returns to starting position during the slow retarded back swing of the sector lever and stop arm from Fig. 15 position to Fig. 14 position. During the first half of this back swing arc 155 supports roller 138 to delay the disc shifting until the weight-actuated disc 20 has come to rest. The notch formed by the inclines 157 and 152 next passes beneath the roller 138. If, as shown in Fig. 10, the pins 24 fail to register with the holes 25, the inward shift of disc 21 is slight, and the roller 138 drops only part way into the notch, further drop being prevented by contact of the pins 24 with solid portions of the wall of disc 20. During the final part of the back swing cam 152 lifts roller 138 back onto the squared end 151 of stop arm 150. This limited shift of disc 21 is insufficient to switch the coin to the user's return chute, and the coin passes to the coin box of the scale. But if, as shown in Fig. 9, the pins 24 do register with the holes 25, the inward shift of disc 21 is greater, and the down movement of bar 130 is then sufficient to carry roller 138 substantially to the bottom of the notch. This greater movement of the disc-shifting mechanism throws a switch across the chute leading to the coin box that deflects the coin to the user's return chute.

Describing next the coin disposal mechanism, which is actuated in part by the pin 167 and in part by the arm 129, 168 (Figs. 1 and 8 to 12) designates a lower portion of the coin chute leading to the coin box 168'. Normally intersecting the chute 168 is a pan 169 having an open outer end. This pan is carried on the outer end of a horizontal bar 170 that is pivoted at its other end to the lower end of a lever 171 which is pivoted at 172 to the bracket plate 148. The upper arm of lever 171 lies across the inward path of movement of the pin 167, and a light pull spring 173 both holds the lever 171 in contact with pin 167 and urges the pan 169 across the coin chute. Communicating with the chute 168 just below the pan 169 is a downwardly inclined branch 174 that opens into a coin return chute 175 from which the coin is delivered to a cup (not shown) on the front wall of the casing 27. At the junction of the branch 174 with the chute 168 is a switch 176 pivoted to the chute 168 at 177 and movable into and out of the chute through a slot 178 in a side wall of the chute. On the lower end of the switch is a tail piece 179 having a hole 180, through which extends a rod 181 the upper end of which rod is pivoted to the arm 129. On the lower end of rod 181 is a knob 182.

Describing the operation of this coin disposal mechanism, in the idle position of the parts shown in Figs. 1 and 8, the arm 129 is in its lowest, approximately horizontal position, and the knob 182 is a considerable distance below the tail piece 179 of the coin switch. If the user fails to guess his correct weight the shift of disc 21 and the lift of rod 181 by arm 129 are so slight

that knob 182 is not raised into contact with the switch, as shown in Figs. 10 and 11, and consequently the coin drops into the coin box 168. But if the user has guessed his correct weight, the swing of the disc-shifting mechanism is greater, and the lift of rod 181 by arm 129 is sufficient to cause the knob 182 to throw the switch to operative position, as shown in Figs. 9 and 12, and this deflects the coin into the return chute.

The invention of this application embodies the same broad principle of operation as that of my pending application Serial No. 265,800; but involves substantial changes and improvements in the structural details and arrangements of the disc-shifting mechanism and the coin-disposal mechanism to adapt these latter mechanisms to cooperative relation and use with the new and improved handle-operated coin-controlled detent release mechanism forming the subject-matter of my application Serial No. 309,355, which latter mechanism may be advantageously employed either on a coin-controlled scale of the type herein shown having a weight-actuated scale disc and a manually set scale disc, or on a coin-controlled scale having only a weight-actuated scale disc. In the invention of this application the means for effecting and controlling the operation of the disc-shifting mechanism from a movable element of the detent release mechanism, and the coin-disposal means and means for operating the same from a movable element of the disc-shifting mechanism, are distinctly novel and improved over the corresponding means disclosed in my application Serial No. 265,800.

Changes and variations in the details of structure and arrangement of parts may be resorted to within the operative principles of the mechanism shown and described and the scope and coverage of the appended claims.

I claim:

I claim:

1. In a coin-controlled weighing scale, the combination with a weight-actuated scale disc and a manually set scale disc disposed side by side with capacity of relative movement toward and from each other, the opposed sides of said discs having the one a hole and the other a pin adapted to enter said hole when identical weight indicating scale marks on the two discs are in register with each other, a detent normally locking said weight-actuated disc against turning, a detent release mechanism including a slidable member, a spring urging said slidable member in one direction, a handle operated push-bar for moving said slidable member in the opposite direction, a coin-controlled control member movable into the path of said slidable member to block complete movement of said slidable member in said opposite direction, and a spring actuated mechanism for shifting one disc toward the other, of a movable stop arm normally blocking working movement of said disc shifting mechanism and formed with a cam for effecting return movement of said disc-shifting mechanism, a pivoted lever and means cooperating therewith to retard the working movement of said disc-shifting mechanism, a lost-motion connection of said lever to said stop arm for shifting the latter into and out of stop engagement with the said disc-shifting mechanism, a spring urging said lever in a direction to move said stop arm into stop engagement, and a second push bar actuated by said slidable member on a complete movement of the latter, for swinging said lever in the reverse

direction and simultaneously tensioning said last named spring.

- 5 named spring.

2. In a coin-controlled weighing scale of the class described, the combination with a weight-actuated scale disc and a manually set scale disc disposed side by side with capacity of relative movement toward and from each other, the opposed sides of said discs having the one a hole and the other a pin adapted to enter said hole

10 when identical weight-actuated scale marks on the two discs are in register with each other, a detent normally locking said weight-actuated disc against turning, a detent release mechanism including a vertically slidable member, a spring exerting a lifting action on said slidable member, a handle-operated depending push-bar for lowering said slidable member, and a pivoted spring-impelled coin-controlled control member movable into the path of said slidable member to block

15 down movement of the latter, of a mechanism, including an endwise slidable vertical bar and a spring urging said bar downwardly, for shifting one disc toward the other, a pivoted lever having on one end thereof an arcuate edge adapted to supportingly engage the lower end of said endwise slidable bar, a stop-arm pivoted coaxially with said lever normally supporting the lower end of said endwise slidable bar and formed with a cam for raising said bar as it engages the latter, a pin and slot connection between said stop-arm and lever by which the latter swings said stop-arm both out of and into supporting engagement with said endwise slidable bar, a spring urging said lever in a direction to move said stop-arm into stop engagement, and a second push-bar having a lost motion connection to and actuated by said vertically slidable member on the down movement of the latter for swinging said lever in the reverse direction and simultaneously tensioning said last named spring.

3. In combination with the subject-matter defined in claim 1, means for delivering a coin comprising a main coin delivery chute, a branch coin return chute, a switch at the junction of said chutes for deflecting coins to said return chute and normally in inoperative position, and means actuated by a movable element of the disc-shifting mechanism for moving said switch to operative position only under the maximum inward movement of said disc-shifting mechanism.

4. In combination with the subject-matter defined in claim 1, means for delivering a coin comprising a main coin delivery chute, a branch coin return chute, a switch at the junction of said chutes for deflecting coins to said return chute and normally in inoperative position, means actuated by a movable element of the disc-shifting mechanism for moving said switch to operative position only under the maximum inward movement of said disc-shifting mechanism, a coin-arresting member slidable across the main chute above the junction of the chutes, a spring urging said coin-arresting member inwardly of the chute, and means actuated by the pivoted lever for withdrawing said coin-arresting member from the chute during the outward movement of the shiftable disc.

5. In a weighing scale having a rotatable weight-actuated disc and a rotatable manually set disc disposed side by side in coaxial relation, and means for shifting said manually set disc toward said weight-actuated disc, said means including a vertical endwise slidable bar and a spring urging said bar downwardly, means to

control the down movement and effect the up movement of said bar comprising a lever pivoted intermediate its ends beneath said bar and formed on its upper end with an arcuate surface adapted to supportingly engage the lower end of said bar while the weight-actuated disc is coming to rest and with an incline at the inner end of said arcuate surface, and a stop arm alongside and freely pivoted coaxially with said lever and formed on its upper end with a cam for raising said bar and beyond said cam a squared end for supporting said bar in its raised position, said incline and cam forming a V-shaped notch to permit down movement of said bar, a lost-motion connection between said lever and stop-arm, and means for rocking said lever in both directions.

6. An embodiment of the subject-matter of claim 5, wherein the means for rocking the lever in one direction is a spring, and the means for rocking it in the reverse direction is a manually operated push-bar.

7. In combination with the subject-matter defined in claim 5, coin-disposal means comprising a coin chute leading to the coin box of the scale, a branch coin return chute, a switch at the junction of said chutes for shunting a coin to said return chute, a member connected to the disc-shifting means adapted to be raised by the latter, and a connection from said member to said switch to move the latter to operative position only under the maximum upward movement of said member.

8. In combination with the subject-matter defined in claim 5, coin disposal means comprising a coin chute leading to the coin box of the scale, a branch coin return chute, a pivoted switch at the junction of said chutes for deflecting a coin into the branch chute, said switch being normally in non-deflecting position, an arm connected to the disc-shifting means adapted to be raised by the latter, and a rod suspended from said arm and having a lost-motion connection to said switch serving to swing the latter to operative position only under the maximum upward movement of said arm.

9. In combination with the subject-matter defined in claim 5, coin disposal means comprising a coin chute leading to the coin box of the scale, a branch coin return chute, a pivoted switch at the junction of said chutes for deflecting a coin into the branch chute, said switch being normally in non-deflecting position, said switch having an apertured tail-piece, a member connected to the disc-shifting means adapted to be raised by the latter, a rod suspended from said member and extending through said apertured tail-piece, and a knob on the lower end of said rod adapted to contact said tail-piece and throw said switch to operative position only under the maximum upward movement of said member.

10. In a coin-controlled weighing scale having a shaft, a weight-actuated disc and a manually

set disc disposed side by side on said shaft, means including a vertical endwise slidable bar and a spring urging said bar downwardly, for shifting said manually set disc toward said weight-actuated disc, a lever pivoted intermediate its ends beneath said bar equipped on its upper end with means for raising and permitting lowering of said bar, and means for rocking said lever in both directions, coin disposal means comprising a main coin chute leading to the coin box of the scale, a branch coin return chute, a normally inoperative switch at the junction of said chutes for shunting a coin to said branch chute, a pan slidable across said main chute above the junction of said chutes for temporarily arresting a coin, a horizontal operating bar connected to said pan, a spring acting on said operating bar to urge said pan across said main chute, means actuated by said pivoted lever for retracting said pan, and means actuated by an element of said disc-shifting means for moving said switch to operative position.

11. An embodiment of the subject-matter defined in claim 10, wherein the means actuated by the pivoted lever for retracting the coin-arresting pan comprises a lateral stud on the lower end of the pivoted lever, and a lever pivoted between its ends with one end thereof operatively connected to the operating bar of the pan and its other end lying across the path of travel of said lateral stud.

12. In a weighing scale, a weight actuated scale disc and a manually set scale disc mounted side by side on a common shaft, said manually set disc being slidable along said shaft, means for shifting said manually set disc toward said weight actuated disc comprising a rock shaft disposed crosswise of said shaft, arms on said rock shaft engaged with the hub of said manually set disc, an endwise slidable bar, lever and link connections from said bar to said rock shaft, and a spring urging said bar in a direction to shift said manually set disc toward said weight actuated disc; and means for returning said manually set disc from its shifted position and retaining it in its returned position, comprising a cam and a support beyond said cam, and means for moving said cam and support successively into engagement with the endwise slidable bar in opposition to the bar-urging spring.

13. An embodiment of the subject-matter defined in claim 12, wherein the means for returning the manually set disc from its shifted position and retaining it in its returned position comprises a lateral stud on the endwise slidable bar, a pivoted stop arm formed with a cam and a squared end beyond said cam, and a spring for swinging said stop arm in a direction to successively engage said cam and squared end with said stud.

BURNS S. WATLING.
